UNITED STATES PATENT OFFICE

90,588

DESIGN FOR AN ELECTRIC FAN

William V. Matthews, McKeesport, Pa., assignor
to Westinghouse Electric & Manufacturing
Company, a corporation of Pennsylvania

Application January 6, 1933. Serial No. 46,747

Term of patent 7 years

To all whom it may concern:

Be it known that I, WILLIAM V. MATTHEWS, a citizen of the United States, residing at McKeesport, in the county of Allegheny and State of Pennsylvania, have invented a new, original, and ornamental Design for an Electric Fan, of which the following is a specification, reference being had to the accompanying drawing constituting a part hereof.

Fig. 1 is a view, in front elevation, of my electric fan, and

Fig. 2 is a view in side elevation, of my electric fan.

I claim:

The ornamental design for an electric fan substantially as shown.

In testimony whereof, I have hereunto subscribed my name this 29th day of December, 1932.

WILLIAM V. MATTHEWS.
